His Attorney.

UNITED STATES PATENT OFFICE

PAUL THIEME, OF BERLIN-WAIDMANNSLUST, GERMANY, ASSIGNOR TO GENERAL ELECTRIC COMPANY, A CORPORATION OF NEW YORK

CIRCUIT PROTECTIVE DEVICE

Application filed December 2, 1929, Serial No. 411,187, and in Germany December 8, 1928.

My invention relates to circuit protective devices and more particularly to such devices having thermal responsive means for controlling the operation thereof in response 5 to overloads or the like.

In switches having thermic over-current release mechanism a more reliable and effective device results if the circuit of an under-voltage magnet is allowed to be interrupted 10 by the overload responsive thermal element so as to effect the disengagement of a pawl or otherwise effect the opening of the switch. In most cases, the under-voltage magnet is already provided since over-current switches 15 are almost always intended to be operated if the voltage of the feed-conductor fails.

However, there are cases in which it is not desired to open the switch in the event of failure of the voltage and the object of the present invention is to provide a thermic releasing device such that on the occurrence of over-current it will interrupt the circuit of the under-voltage magnet, but in its position of rest mechanically locks the armature of the 25 under-voltage magnet in order to prevent a release of the switch if the voltage fails without the simultaneous occurrence of over-current.

The single figure of the drawing is a circuit 30 diagram schematically illustrating one embodiment of the invention.

In the drawing 1 designates a bimetallic strip which is heated by a heater 2 energized in accordance with the current in the lines L_1 , 35 L_2 to be controlled. The free end 3 of the thermal element is arranged to bend towards one side at a certain temperature. On the free end 3 of the bimetallic strip 1 a contact maker 4 rests, the projection 6 of which is 40 pressed into engagement with the end 3 of the bimetallic strip by a spring 5. In the position of rest illustrated the contact-maker 4 bridges the terminals 8 and 9 by means of a contact plate 7. Terminals 8 and 9 are connected in the energizing circuit of the winding 10 of the under-voltage magnet 11. The armature 12 of the under-voltage magnet 11 45 for the circuit interrupting switch S is under the influence of a spring 13 which tends to pull it so as to release the latch L holding the

switch in the closed position. A locking pawl 14, however, prevents this movement of the armature 12. In addition, the armature 12 of the under-voltage magnet is held by the magnetic flux generated by the winding 10. 55

If over-current occurs in the circuit supplied by conductors L_1 , L_2 , the bimetallic strip 1 is heated and bends to one side, so that the contact member 4 can follow the pull of the spring 5. Upon the initial movement 60 of the contact-imparting member 4, the projection 15 engages an arm of the pawl 14 and releases the armature 12. Then the bridging contact 7 of the terminals 8 and 9 is disengaged so that the under-voltage magnet 11 65 no longer retains the armature 12. Thus, after first unlatching the armature and then deenergizing the holding electromagnet, the release of the switch can take place in the known manner, either mechanically by the 70 release of a pawl-device L as illustrated or electrically by switching in a releasing winding. For the sake of simplicity, the releasing winding arrangement has been omitted from the drawing. 75

What I claim as new and desire to secure by Letters Patent of the United States is:

1. A circuit protective switch having a thermal overcurrent responsive element and an under-voltage operating electromagnet 80 characterized in that the energizing circuit of the under-voltage electromagnet is interrupted on the occurrence of over-current by the thermal element and that the armature of the under-voltage electromagnet is normally retained by a locking device which, on the occurrence of over-current is freed by the thermal element. 85

2. In combination, an electroresponsive device, a movable member controlled thereby, 90 separate means for controlling movement of said member, and thermal responsive means for first rendering said separate means ineffective and then controlling the energization of said first electroresponsive means to effect movement of said member. 95

3. A circuit protective device comprising means for opening the circuit, electroresponsive means energized from the circuit for controlling the circuit opening means, re- 100

- straining means normally preventing operation of said electroresponsive means, and thermal current responsive means energized in accordance with the current in the circuit
- 5 for first rendering said restraining means ineffective and then controlling the energization of said electroresponsive means to effect operation of the circuit opening means to open the circuit.
- 10 4. In combination, a circuit interrupter having a normally energized releasing electromagnet, a latch normally preventing operation of said electromagnet, and thermal overload current responsive means for releasing the latch and deenergizing the releasing electromagnet to effect operation of the circuit interrupter.
- 15 5. In combination, a circuit interrupter, a movable member biased to effect operation thereof, a normally energized electromagnet for holding said member against its bias, a latch for holding said member against its bias, a separate movable member biased to release said latch and having a contact for deenergizing said holding electromagnet, a thermal responsive latch for holding said separate movable member against its bias and an electrical heater energized in accordance with the current in the circuit controlled by the interrupter for heating said thermal responsive latch.
- 20 6. In combination, a normally energized electromagnet, a biased movable magnetic member held thereby against its bias, a latch for holding said member against its bias, and thermal responsive means connected to be energized in accordance with predetermined electrical conditions for first releasing said latch and then controlling the energization
- 25 of said electromagnet to permit movement of said member in accordance with its bias.
7. A circuit protective device comprising means for opening the circuit, a movable member biased to effect operation of said
- 30 circuit opening means, a normally energized electromagnet for holding said member against its bias, separate latching means for holding said member against its bias, and thermal responsive means for first rendering
- 35 said latching means ineffective and then controlling the energization of said electromagnet to release said member for movement in accordance with its bias.

In witness whereof, I have hereunto set
55 my hand this 16th day of November, 1929.
PAUL THIEME.
